CLAIM

The ornamental design for a spinning disc and spindle toy, as shown and described.

DESCRIPTION

FIG. 1 is a top front perspective view of a first embodiment of a spinning disc and spindle toy, showing my design; FIG. 2 is a top plan view thereof;

FIG. 3 is a bottom plan view thereof;

FIG. 4 is a front elevation view thereof, the rear elevation view being a mirror image thereof;

FIG. 5 is a right elevation view of FIG. 1, the left elevation view being a mirror image thereof;

FIG. 6 is an enlarged detail view of FIG. 1;

FIG. 7 is a cross sectional view taken along line 7-7 of FIG. 1;

FIG. 8 is a top front perspective view of a second embodiment of my design;

FIG. 9 is a top plan view thereof;

FIG. 10 is a bottom plan view thereof;

FIG. 11 is a front elevation view thereof, the rear elevation view being a mirror image thereof;

FIG. 12 is a right elevation view thereof, the left elevation view being a mirror image thereof;

FIG. 13 is an enlarged detail view of FIG. 8;

FIG. 14 is a cross sectional view taken along line 14-14 of FIG. 8;

FIG. 15 is a top front perspective view of a third embodiment of my design;

FIG. 16 is a top plan view thereof;

FIG. 17 is a bottom plan view thereof;

FIG. 18 is a front elevation view thereof, the rear elevation view being a mirror image thereof;

FIG. 19 is a right elevation view thereof, the left elevation view being a mirror image thereof;

FIG. 20 is an enlarged detail view of FIG. 15;

FIG. 21 is a cross sectional view of FIG. 15, taken along line 21-21 of FIG. 15;

FIG. 22 is a top front perspective view of a fourth embodiment of my design;

FIG. 23 is a top plan view thereof;

FIG. 24 is a bottom plan view thereof;

FIG. 25 is a front elevation view thereof, the rear elevation view being a mirror image thereof;

FIG. 26 is a right elevation view thereof, the left elevation view being a mirror image thereof;

FIG. 27 is an enlarged detail view of FIG. 22;

FIG. 28 is a cross sectional view taken along line 28-28 of FIG. 22;

FIG. 29 is a top front perspective view of a fifth embodiment of my design;

FIG. 30 is a top plan view thereof;

FIG. 31 is a bottom plan view thereof;

FIG. 32 is a front elevation view thereof, the rear elevation view being a mirror image thereof;

FIG. 33 is a right elevation view thereof, the left elevation view being a mirror image thereof;

FIG. 34 is an enlarged detail view of FIG. 29;

FIG. 35 is a cross sectional view taken along line 34-34 of FIG. 29;

FIG. 36 is a top front perspective view of a sixth embodiment of my design;

FIG. 37 is a top plan view thereof;

FIG. 38 is a bottom plan view thereof;

FIG. 39 is a front elevation view thereof, the rear elevation view being a mirror image thereof;

FIG. 40 is a right elevation view thereof, the left elevation view being a mirror image thereof;

FIG. 41 is an enlarged detail view of FIG. 36; and,

FIG. 42 is a cross sectional view taken along line 42-42 of FIG. 36.

The even length dashed lines in the drawings depict portions of the spinning disc and spindle toy that form no part of the claimed design. The alternating length dashed lines in the drawings depict the boundary of the claim; and it is understood that the claim extends to the boundary that forms no part of the claimed design.
